(57) CLAIM

We claim the ornamental design for file or draft holder, as shown and described.

DESCRIPTION

FIG. 1 is a perspective view from above and front of the holder in raised position showing our new design;

FIG. 2 is a view straight from behind the holder in raised position;

FIG. 3 is a perspective view obliquely from behind in lower position of the holder; and,

FIG. 4 is a lateral view of the holder in raised position.
